Primary Examiner — Natasha Vujcic

(57) **CLAIM**

The ornamental design for nozzle for spraying fluids, as shown and described.

DESCRIPTION

1. Nozzle for spraying fluids
- 1.1 is a bottom view.
- 1.2 is a right side view.
- 1.3 is a right side perspective view.
- 1.4 is a front view.
- 1.5 is a rear view.
- 1.6 is a top view.
- 1.7 is a left side view.
- 1.8 is a rear perspective view
- 1.9 is a top perspective view.
